UNITED STATES PATENT OFFICE.

THURE LARSSON, OF WORCESTER, MASSACHUSETTS, ASSIGNOR TO NORTON COMPANY, OF WORCESTER, MASSACHUSETTS, A CORPORATION OF MASSACHUSETTS.

Mounting for Segmental Wheels.

Application filed October 29, 1924. Serial No. 746,696.

My invention relates to grinding wheels of the ring or cylinder type which are used for plane surface grinding.

Hereofore, abrasive rings for plane surface grinding have been cemented in a ring support or fastened thereto by cumbersome devices. For certain grinding operations, the use of segments instead of a solid ring is preferred, and even greater difficulties than those met in fastening an abrasive ring in place are encountered in providing a satisfactory mounting for the spaced segments. If the abrasive segments are cemented in place, difficulties are encountered in removing them from the ring when worn out or when breakage occurs. If fastened removably in place, there is a danger of their becoming loosened from the setting.

It is accordingly one object of my invention to provide a simple and economically manufactured construction which will hold the segments on a driving ring so as to insure the maximum wear with one setting thereof, and particularly to mount the segments in such a manner that they may be easily removed and replaced.

With this and other objects in view as will be apparent to one skilled in the art, my invention resides in the combination of parts set forth in the specification and covered by the claims appended hereto.

Referring to the drawings, in which like references indicate like parts:

Figure 1 is a sectional view on the line 1-1 of Fig. 2 of a driving ring having abrasive segments mounted thereon; and

Fig. 2 is a plan view showing the arrangement of the segments and their fastening devices.

In accordance with my invention, I propose to employ abrasive segments suitably shaped for mounting on a metal ring and to hold them firmly in place between an annular flange on the ring and a set of adjustable blocks which clamp the segments against the ring.

Referring to the drawings, I have illustrated one embodiment of my invention comprising a driving head, fashioned as a metal ring 10 which is adapted to be fastened by set screws 11 passing through a flange 12 fixed on the driving spindle 13 of a grinding machine. In order that abrasive segments may be fastened to this ring, I provide the ring 10 with a depending annular flange 14.

A set of abrading segments 15 are disposed around the ring 10 and arranged to be held in place against the locating flange 14. The flange is narrow and the segments project below the same for performing the grinding operation and only so much of the segment is hidden behind the flange as is considered necessary for clamping it in place.

I propose to clamp the segments against this flange by means of adjustable blocks arranged to contact with the inside of the segments. While various expedients may be employed for preventing removal of the segments after they have been clamped, I prefer to form the segments with enlarged heads 16, and the flange 14 may be suitably provided with an inwardly projecting portion or face 17, which may be accomplished by bending the flange inwardly, so that the flange will fit against the outer faces 18 of the segments.

The inner faces 19 of the segments are engaged by clamping blocks 20 which are also so shaped and arranged as to fit thereagainst. These blocks 20 may be adjustably positioned by means of screw threaded bolts or cap screws 21 which pass through the spaces between adjacent ends of the segments and through the ring 10. The screws slope in the direction illustrated so that any pressure on the clamping blocks caused by tightening the screws will be transmitted to the surfaces 19 of the segments in such a direction as to force the segments against the outer flange and the under surface 22 of the ring. Each block, as illustrated, laps over the ends of two adjacent segments, thereby giving greater freedom in adjusting the segments in place. The flange 14 and the clamping blocks 20 may each be provided with facings 23 and 24 respectively of soft metal, such as lead, where they contact with the abrasive segments and thereby reduce the liability of fracture when subjected to excessive pressure.

It will now be apparent that I have provided a simple means of fastening abrasive segments to a ring or chuck and that old segments may be readily taken out and new ones inserted. This construction may be quickly assembled and it will not require any of the operator's time for adjustments. The

abrasive segments are clamped against fixed parts of the driving head, i. e. the flange 14 and the under side 22 of the head, thereby insuring rigidity of structure and that the 5 segments will be correctly located.

Having thus described my invention, what I claim as new and desire to secure by Letters Patent is:

1. An abrasive wheel comprising a rotatable driving head having an annular flange, a plurality of abrasive segments having enlarged heads thereon, and clamping blocks adjustably mounted on said head and arranged to wedge the segments against said flange and head and removably fasten them rigidly in position.
2. An abrasive wheel comprising a rotatable driving head having a flange provided with an inwardly inclined surface, a plurality of abrasive segments having wedge

shaped heads arranged in contact with said flange surface, clamping blocks engaging the inner faces of the segment's heads, and means to adjustably fasten said blocks to the driving head and wedge the segments in position against said head and flange.

3. An abrasive wheel comprising a rotatable driving head, an annular flange thereon having an inwardly projecting portion, a set of spaced abrasive segments having enlarged heads contacting with said flange portion, clamping blocks engaging the inner sides of adjacent pairs of segments and bolts for the blocks passing through the spaces between the segments and adjustably engaging the driving head to wedge the segments in position against the head and flange.

Signed at Worcester, Massachusetts, this 27th day of October, 1924.

THURE LARSSON.
